ROTARY RETRACTING SOOT BLOWER
CONSTRUCTIONHarry E. Brelsford, Birmingham, Mich., assignor
to Diamond Power Specialty Corporation, De-
troit, Mich., a corporation of Michigan

Application January 24, 1946, Serial No. 643,055

12 Claims. (Cl. 15—317)

1

The present invention relates to improvements in soot blower construction.

One of the primary objects of the present invention is to provide an improved soot blower construction which is particularly adapted for use in the hottest part of the furnace and which is so constructed and arranged so as to increase its life.

A further object of the invention is to provide improvements in soot blower constructions of the type mentioned in which the blower is projected into the furnace only during the blowing operation and is protected in a retracted position when not operating.

Another object of the invention is to provide improvements in soot blower constructions of the type mentioned which will permit making a securely sealed joint where the blower enters the furnace wall, thereby preventing leakage of gases from the furnace outward or the leakage of air from the outside into the furnace.

Another object of the invention is to provide improvements in soot blower constructions of the type mentioned in which the traveling member is securely held so that all strain against this traveling member is restrained by means rigidly related and so as to relieve the communicating member from all strain.

Another object of the invention is to provide improvements in soot blower constructions of the type mentioned in which the traveling member is restrained until it reaches the desired travel and then is released for any desired number of rotations so that the particular cleaning cycle may be followed.

A further object of the invention is to provide improvements in soot blower constructions of the type mentioned in which there is provision for accessibility to the valve without interference to the piping.

Another object of the invention is to provide improvements in the soot blower constructions of the type mentioned which will permit ready operation of the valves against high pressure through relatively slight effort on the part of the motive means of the blower itself.

Other objects of the invention will become apparent from the following specification, the drawings relating thereto, and from the claims hereinafter set forth.

In the drawings, in which like numerals are used to designate like parts in the several views throughout,

Fig. 1 is an end elevational view of a soot blower construction embodying features of the present invention;

Fig. 2 is a cross-sectional view, with parts in elevation, taken substantially along the line 2—2 of Fig. 1 and showing the construction in its relationship to the furnace wall;

2

Fig. 3 is a cross-sectional view taken substantially along the line 3—3 of Fig. 2; and

Fig. 4 is a cross-sectional view taken substantially along the line 4—4 of Fig. 2.

It is frequently desirable to place soot blowers on the sides of boilers or furnaces so that they may project into the hottest part of the combustion space in order to direct the cleaning fluid onto the underside of the generating tubes, or other parts of the boiler, and where the location is so hot that the blower cannot remain in the furnace but must be retracted as soon as the blowing medium is discontinued. There are various types of such blowers, some which have very long travels, up to twenty feet, and others that require much less travel when it is desired only to clean heating surfaces close to the furnace walls. The present invention is directed to the latter type and has a travel of approximately twelve inches forward toward the boiler from its retracted position. This is sufficient to retract the nozzle into the boiler wall space where it is protected from the heat while it is inoperative and yet allows it to project sufficiently into the combustion space so as to efficiently direct the cleaning fluid onto the surfaces of the boiler to be cleaned.

Because of the nature of the service, it is desirable that the cleaning fluid be turned on automatically as soon as the nozzle reaches its maximum projection and before it becomes appreciably hotter so as to endanger its life. It is therefore necessary that such a head be automatically valved in order to protect it from the heat, as well as from the standpoint of efficiency in use of the cleaning medium. Such a head may be either manually or power controlled, and in either case it is desirable that the traversing motion be fairly rapid to conserve time as well as effort, because when power controlled by a power motor, the speed is fixed and the time interval of traversing becomes a definite, fixed interval and becomes important where there are a great many units on a boiler to be operated in a given time. The construction of the present invention thus provides a head with the necessary travel, with the means for rapidly producing this travel, and of a rugged construction which permits maintenance of rigidity and relative position while blowing. The construction of the present invention also lends itself either to manual or power operation.

Also, in general, the construction of the present invention is one which permits making a securely sealed joint where the blower enters the furnace wall and prevents leakage of gases from the furnace outwardly or from the outside inwardly. The projecting element has a smooth, uninterrupted exterior which permits of a packed joint to accomplish this. Furthermore, when fully ex-

tended the nozzle part of the head is rigidly supported in the head structure and therefore does not impose any strain on the telescopic arrangement of the two tubes with consequent damage to the packing which seals the joints between the two tubes. Also, a rigid construction is provided which takes the reaction forces when the blowing medium is being discharged. Furthermore, inasmuch as steam pressures are continually increasing, it is becoming more and more difficult to directly open a valve under high pressure because of the excessive force required and, therefore, according to the present invention, a self-opening valve is provided which is controlled by a pilot valve operating through the medium of an unbalanced piston. The blowing medium is introduced to the head structure transversely of the valve axis, as compared to axially thereof, and it is, therefore, not necessary to disturb the piping connections to this head for access to the valve for regrinding, or other attention.

Referring to the drawings, the blowing head is generally indicated at 1 and is adapted to be mounted to the exterior surface of a furnace wall adjacent an opening communicating with the interior thereof, in the usual way. The furnace wall (not shown) has an opening therethrough which communicates with the combustion space within the furnace, and in the present instance it may be considered that this is the hottest part of the furnace.

The head 1 includes a frame portion in the form of a casting 3. The casting 3 is formed with a fluid inlet chamber, including an upper portion 4 and a lower portion 5. A laterally extending inlet opening 6 communicates with the chamber 5 and has connected thereto a conduit 7 which carries the cleaning medium through the inlet 6 into the chamber 5. Chambers 5 and 6 are separated by valve means which includes a valve seat member 8 which is threaded into a threaded annular flange formed in the casting 3 between chambers 5 and 6. The lower peripheral edge of the member 8 forms the valve seat against which a valve 9 bears to close communication between chambers 4 and 5. When the valve 9 is moved away from the valve seat 8, communication is established between chambers 4 and 5.

Valve disk 9 is mounted on a stem 10, and such stem 10 is loosely connected at its lower end with a piston 11 by means of a lock washer 12 and a lock nut 13. The looseness is between the periphery of the stem 10 and the opening through the lock nut so that there may be no binding in movement of the plunger. The lock nut 13 is secured against loosening by means of a locking disk 14.

The stem 10 extends through a central aperture in disk 9, and such valve disk seats on a tapered shoulder 15 on the valve rod 10 and is ground to a tight joint on the shoulder. The intermediate portion of the valve stem is reduced and threaded, and lock nuts 16 are received on the threaded portion adjacent the upper face of the valve disk 9 so that the valve disk 9 is moved in either direction due to the engagement of shoulder 15 or the underlock nut 16, as the case may be. The lock nuts may be adjustably positioned on the threaded portion so that any desired degree of freedom or slight lost motion may be imparted to the disk 9.

The upper and reduced end of the valve stem 10 is indicated at 17 and is guided in a guide bushing 18 which is threaded through a threaded opening in the casting at the top of chamber 4 in axial alignment with the valve stem. The

guide bushing 18 is vented as indicated at 19 so as to prevent compression of the blowing medium in the space between the end of the valve stem and the end of the guide passage.

Piston 11 is reciprocably mounted within a bore 20 formed in the casting 3 and communicating through the lower side with chamber 5. An end plate 22 is bolted to the lower end of the casting adjacent the bore 20 by means of bolts 23. The piston 11 is forced upwardly, or to its valve-closing position, by means of a compression spring 24 so as to seat the valve disk 9 against its valve seat. A stop rod 25 is mounted centrally on the end plate 22 and projects upwardly within the bore 20 so as to limit the downward movement of the piston 11, together with the operating parts connected thereto. The piston 11 is not a perfectly tight fit within the bore, it being intended that there would be some leakage past this piston into the bore 20 so that there will be equalization of fluid pressure between chamber 5 and the chamber formed by bore 20. The particular function of this will be more apparent from a later description.

A throttling disk 26 is threadably mounted on the bushing 18 within the chamber 4 and adjacent the top edge of valve member 8. By adjusting the orifice disk 26 on the member 18, any desired clearance between itself and the exit side of the valve seat 8 may be provided so as to give the desired throttling of the blowing medium when pressure on the discharge side of the valve is to be less than the supply pressure. The periphery of the disk 26 is formed with depressions at spaced intervals therearound, and it may be secured in any position by means of a stop screw 27 (Fig. 1) which extends within chamber 4 and the end of which projects within one of the depressions in the periphery of the disk 26.

The casting 3 is formed with cleaning fluid passageway 28, the end of which is in open communication with chamber 4. The outlet end communicates through a horizontal opening 29 formed in a flange portion 30 of the casting.

A bracket 31 is connected to the opposite end of the casting by means of cap screws 32 and terminates in upwardly, extending and laterally, spaced projecting portions 33 and 34.

The entire blowing unit 1 is mounted to the exterior surface of the furnace wall against the usual wall box fitting by bolts extending through the flange of portion 34.

In general, the projecting means includes a pair of telescoping members, the exterior one of which has a blowing nozzle 35 connected to the end thereof. Such telescoping members are indicated at 36 and 37. Member 36 is a tubular member, circular in cross section, and having a thread 38 formed on the outside surface intermediate the ends thereof. The left-hand end of member 36 is received within opening 39 formed in flange 30, and packing 40 is disposed between the outer surface of member 36 and the inner surface of opening 39. The tube 36 is secured against axial movement by means of a thrust bearing 41. The thrust bearing 41 is mounted between a flanged member 42, which is secured to flange 30 by means of bolts 43, and an annular member 44. The flange member 42 has an inwardly extending annular flange 45 which engages the outer surface of the outer bearing race. Member 44 has an axially directed annular flange 46 which engages the adjacent face of the inner bearing race. The inner end of packing 40 abuts against a bearing

ring 47 which in turn abuts against the annular shoulder in casting 3 adjacent opening 29. The opposite end of the packing abuts against a shoulder flange on member 44 which is telescopically received within opening 39 of flange portion 30.

A driving member 48, in the form of a pulley in the embodiment illustrated, has a hub portion 49 within which the tubular member 38 is received. Such member 48 is secured to the member 36 by means of screws 50, so that the member 36 rotates with the driving means 48. The left-hand end of the hub portion 49 telescopically receives thereon the bearing races of the thrust bearing 41. The outer bearing race abutting against a shoulder formed on the hub 49, and the inner bearing race is secured in place by means of a snap ring 51. Since tubular member 38 is fixed to member 48, which in turn has the thrust bearing axially fixed with respect thereto, and since the flange 45 of the member 42 axially fixes the thrust bearing to the flange 30 of casting 3, it will be evident that the member 36 is held against axial movement, but may rotate with respect to casting 3.

The right-hand end of the tubular member 36 is supported within the telescoping member 37. Such end of member 36 is reduced and has a packing 52 embracing the reduced end and held in place by bearing rings 53 and 54. Bearing ring 53 abuts against an adjacent shoulder formed in member 36, and ring 54 is held in place by means of a snap ring 55. Axial and rotative relative movement between members 36 and 37 is thus permitted.

Member 37 is circular in cross section and has a smooth, uninterrupted, exterior surface. It projects through an opening 56 formed in bracket portion 33 and also projects through an axial opening in bracket portion 34. The end of member 37 is threaded and has the nozzle 35 threaded thereto. The member 37 is adapted to be moved within the furnace to its projected position and retracted therefrom, to the position shown in Fig. 2, so that the nozzle 35 is disposed within the opening in the furnace wall when the blower is not operating. The right-hand end of member 37 is guided by means of a guide bushing 57 which is mounted within flange portion 34.

Sealing means 58 embrace the tubular member 37 and are disposed between the exterior surface of the member 37 and the adjacent wall of the opening through portion 34. The sealing means abut against a shoulder formed on an inwardly directed annular flange 59, and the opposite end of the packing is held in proper position by means of a packing gland follower 60. Gases from the furnace, therefore, cannot escape past the packing 58, nor can air enter the furnace from the outside past packing 58, while the member 37 is free to be moved to and from its projected and retracted positions.

The opposite, or left-hand, end of member 37 is fixed to the hub of an actuating member 61, as by a weld 62, for example. The actuating member 61 has a disk portion 63 and a hub portion within which the tubular member 37 is received. The hub portion also has an annular, finished portion 64 which is adapted to be received within opening 56 and bear against bushing 65, within opening 56, when the tubular member 37 is extended to its projected position. Since portions 33 and 34 are spaced from each other, it will, therefore, be appreciated that when the tubular member 37 is extended to its projected position, it is supported within spaced bearings so that the projecting end of the nozzle is rigidly

supported and does not cause undesirable loads on the operating means.

The actuating member 61 has an annular member 66 fixed thereto by means of screws 67, and such member 66 has a projection 68 formed on the inner surface thereof which is received within the thread 38 and provides a follower nut to cause axial movement of the member 37 when member 36 is rotated.

The member 37 is restrained against rotative movement until it reaches its full, extended position, at which time it is released so that it may rotate to effect the blowing operation. This is accomplished through the interrelationship between disk member 63 and a pivotally mounted bar 69. The disk 63 has a notch 70 formed in the periphery thereof which is adapted to receive the rod 69 therein. When the rod 69 is engaged within the notch 70 and the rod is held against movement, the disk 63 cannot rotate, as one of the walls of the notch will abut against the rod 69. The rod 69 extends axially of tube 37 so that the tube 37 and member 61 may move axially, even though they cannot rotate until a particular position is reached.

The rod 69 has depending pivot arms 71 fixed thereto which in turn have pivot openings therethrough. A pivot rod 72 is mounted on upwardly directed lugs 73 formed in the casting 3 and serves to pivotally mount the rod 69. The right-hand end of rod 72 projects within an aligned opening 74 formed in bracket 31. The rod 69 is normally urged to its upper position by means of a spring 75 which is wound around rod 72 and has one end thereof bearing against the rod 69 and the other end thereof fixed by abutment against the adjacent surface of casting 3. Viewing Fig. 3, the spring acts to pivot the rod 69 in a clockwise direction.

The tendency of the action of member 36 as it rotates is to turn the disc 63 in a clockwise direction, viewing Fig. 3. The rod 69 is restrained from movement in that direction by means of a stop 76 (Figs. 2 and 4). The stop 76 has a recess 77 within which the end of bar 69 normally projects, the recess being defined by rearwardly extending projections 78, 79 formed integrally upon the stop member. Projection 78 prevents pivotal movement of the bar 69 in the indicated direction during advancing movement of the nozzle and until the projection 78 is moved out of the way by bodily forward movement of the stop structure, which movement is induced by the front face of cam disc 63. The forward end of the rod 69 then swings across and lies in facing relation to the adjacent rear end face of the projection 78 when the rod is pivoted to the position shown in broken lines in Fig. 3.

The stop 76 is formed with a notch 80 in the lower edge within which the pivot rod 72 is received. This connection between the stop 76 and the rod 72 prevents rotative movement of the stop 76, but permits axial movement thereof along rod 72.

The stop 76 has a sleeve 81 fixed thereto which is slidably received within an axially-aligned opening 82 formed in bracket 31. A compression spring 83 is disposed within the opening 82, and one end of the spring abuts against the bottom of the opening and the opposite end abuts against a pin 84 which is fixed to member 16. Thus, the spring 83 normally urges the stop 76 toward the rear or left (viewing Fig. 2).

The manner in which the stop 76 is moved to

its out-of-the-way position will be described in greater detail hereinafter.

The pivoting of the rod 69 and the length of the time that it is held in its pivoted position controls the opening of valve 9, and therefore the introduction of the cleaning medium through the nozzle into the furnace. The pivoting of the rod 69 controls the operation of a pilot valve 85 which is mounted on casting 3. The pilot valve is formed with an inner chamber and a valve seat 86. A disk valve 87 is disposed within the valve chamber and is normally urged toward the seat 86 by means of a spring 88. The valve has a stem 89 which extends upwardly through a packed opening in the top of valve body 85 to a position under an actuating arm 90. The valve 85 is laterally offset from the axis of the pivot shaft 72, and the arm 90 is fixed to the pivot rod 69 so that as the pivot rod pivots, as shown in Fig. 3, the actuating arm 90 engages the upper end of stem 89 and depresses the stem to open valve 87. The chamber within the valve above the valve seat is vented to the atmosphere through an opening 92. The chamber within the valve body on the underside of the valve 87 is connected through a conduit 93 with an opening 94 through end plate 22. Opening 94 communicates with the chamber formed by bore 20 under plunger 11.

The wheel 48 may be turned either by hand or it may be motor-driven. It may be in the form of a pulley, or a chain sprocket so that it may be turned by hand.

In the operation of the device, assuming that the member 37, together with the nozzle, is in its retracted position, the valve 9 is closed, the cleaning fluid cannot pass into chamber 4 and through passageway 28 into and through the hollow interior of members 36 and 37 and nozzle 35. When the valve 9 is opened it will, of course, be understood that the fluid follows this path and is discharged through the openings in the nozzle head into the furnace and against the surfaces to be cleaned. Upon rotation of wheel 48, either by hand or motor, the member 36 is also rotated. The relationship between thread 38 and nut 68 will cause the nut, together with members 61 and 37, to travel axially of member 36 toward the projected position. At this time, the stop 76 is in its restraining position shown in Fig. 2, so that the rod 69 cannot pivot, and such rod is received within the notch 70 with one wall of the notch bearing thereagainst. This continues until the disc 63 reaches the position to abut against the facing side of stop 76. Continued axial movement of member 37, together with member 61, causes the disc 63 to force the stop 76 to the right against spring 83. It is forced to that position until the end of rod 69 is released from abutment against the one side of recess 71 and is free from projection 78. As soon as the rod 69 is freed so that it may pivot, disc 63 is also free to turn and during the initial portion of its rotary movement will cause rod 69 to pivot about its pivot pin 72, as shown in Fig. 3, and cause depression of valve stem 89 so as to vent valve 85 to the atmosphere. The underside of piston 11 is at the same time vented to atmosphere through opening 94 and conduit 93. As mentioned above, as soon as the pressure under piston 11 is vented to the atmosphere, the fluid pressure within chamber 5 from the cleaning medium will instantly move the plunger downwardly to open valve 9 and permit the passage of the cleaning fluid into chamber 4, passageway 28, and to the cleaning

nozzle through members 36 and 37. The cleaning nozzle thereafter rotates with member 37 in response to continued turning of wheel 48 while the cleaning medium is passing through the openings therethrough. The valve 85 will be held vented to atmosphere and the unnotched periphery of disc 63 rides over the rod 69, holding it in notch 70 again reaches a position so that the spring 75 may return the rod to its upper position within the notch. Continued forward rotation of the disk (in the same direction as the wheel 48 was turned to project the nozzle) is effective to maintain bar 69 and arm 90 cocked and valve 87 open throughout such part of each such forward revolution as bar 69 is out of cam notch 70, and blowing may thus be continued for any number of revolutions, although during each such revolution blowing steam is only discharged while the bar is cocked by the higher parts of cam disc 63, and is stopped when the bar is raised into the notched portion of the cam by the spring 75. The time in which the actual blowing takes place depends upon the length of the cut away or notched portion 70 of the disc, being shorter as such notch is lengthened peripherally. It is illustrated in the drawings of a very small length, but it may extend around the periphery of the disk up to, for example, 180°.

It will be understood, of course, that the driving member 48 is rotated at a more or less uniform rate, and, as soon as the rod 69 is not supported by the periphery of cam 63, the spring 75 will swing the rod in a counterclockwise direction on its pivot pin 72, as viewed in Fig. 4, or in a clockwise direction from the broken line to the full line position as shown in Fig. 3. This movement of the rod 69 releases the pressure of the actuating arm 90 from the valve stem 89, thus permitting the spring 87 to close the pilot valve 85, and thus the main valve 9. In this wise, it is seen that the peripheral length of the notch 70 determines the portion of a revolution of the cam 63 during which blowing fluid is not discharged.

Reversal of rotation of the member 48 will cause retraction of member 37, together with disk 63. This will permit the stop 76 to move back to the position shown in Fig. 2, in which position the rod 69 cannot pivot after it has once come back into slot 70. Continued rocking of the rod 69 in a reverse (clockwise) direction past a vertical position, as shown in full lines in Fig. 3, is prevented by the projection 79 on stop 76 engaging against the forward arm 71, such rocking movement being in a counterclockwise direction as illustrated in Fig. 4, which is a view taken looking in a direction opposite to that of Fig. 3. Projection 79 is longer than projection 78 so that it always overlaps the bar 69 and front arm 71 as shown in Fig. 2. Further reverse rocking movement of the rod 69 beyond the vertical position being restrained, it follows that further rotation of cam 63 is prevented when abutted by the wall at the opposite end of notch 70 from the end which serves to initially cock the bar. Thereupon, further reverse rotation of the driving member 48 causes relative rotation between the threaded tube 36 and the blower element 37, which will cause retraction of the blower element. Continued rotation of the wheel 48 in the reversed direction will effect movement of member 37 to its fully retracted position shown in Fig. 2. When the valve 87 is closed, the above-mentioned leakage past piston 11 will equalize the pressures

on both sides thereof so that the spring 24 may act with ease to close valve 9.

What is claimed is:

1. A soot blower construction comprising a housing, means providing a fluid inlet chamber within said housing, valve means controlling the flow of fluid through said chamber, a fluid passageway within said housing communicating with said chamber, an externally threaded tubular member mounted on said housing and communicating with said passageway, another tubular member adapted to have a nozzle mounted thereon telescopically embracing said threaded tubular member and mounted thereon for axial and rotative movement with respect thereto so that it may move to projected and retracted positions, said another tubular member having a smooth, uninterrupted exterior surface, means connected to said another tubular member and engaging the thread on said threaded tubular member to effect axial movement of said another tubular member upon rotation of said threaded tubular member, an actuating member connected to said another tubular member for movement therewith, means to effect rotation of said threaded tubular member, movable means connected to said actuating member to restrain rotation of said another tubular member until it reaches its projected position, means to prevent movement of said movable means until engaged by said actuating member when said movable means is released for movement, and means responsive to the movement of said movable member to effect actuation of said valve means.

2. A soot blower construction comprising a housing, means providing a fluid inlet chamber within said housing, normally closed valve means controlling the flow of fluid through said chamber, a fluid passageway within said housing communicating with said chamber, an externally threaded tubular member mounted on said housing and communicating with said passageway, another tubular member adapted to have a nozzle mounted thereon telescopically embracing said threaded tubular member and mounted thereon for axial and rotative movement with respect thereto so that it may move to projected and retracted positions, said another tubular member having a smooth, uninterrupted exterior surface, means connected to said another tubular member and engaging the thread on said threaded tubular member to effect axial movement of said another tubular member upon rotation of said threaded tubular member, a disc member having a notch in the periphery connected to said another tubular member for movement therewith, means to effect rotation of said threaded tubular member, a pivotally mounted bar engageable in said notch and extending longitudinally of said another tubular member to restrain rotation of said another tubular member until it reaches its projected position, means to prevent pivotal movement of said bar until engaged by said disc member when said bar is released for movement, and means responsive to the movement of said tubular member to open said valve means.

3. A soot blower construction comprising a housing having a passageway and a fluid inlet to the passageway, valve means controlling the flow of fluid to said passageway, an externally threaded tubular member rotatably mounted on said housing and communicating internally with said passageway, a second tubular member adapted to have a nozzle mounted thereon tele-

scopically embracing said threaded tubular member and mounted thereon for axial and rotative movement with respect thereto, said second tubular member having a smooth, uninterrupted exterior surface, means connected to said second tubular member and engaging the thread on said threaded tubular member to effect axial movement of said second tubular member upon rotation of said threaded tubular member, means to effect rotation of said threaded tubular member, keying means to restrain rotation of said second tubular member until it reaches one end of its travel, including a common keying and valve actuating element movable concurrently with said second tubular member, and means for actuating said valve in response to movement of said element.

4. A soot blower construction comprising a housing having a passageway and a fluid inlet to the passageway, valve means controlling the flow of fluid to said passageway, an externally threaded tubular member mounted on said housing and communicating internally with said passageway, a second tubular member adapted to have a nozzle mounted thereon telescopically embracing said threaded tubular member and mounted thereon for axial and rotative movement with respect thereto, said second tubular member having a smooth, uninterrupted exterior surface, means connected to said second tubular member and engaging the thread on said threaded tubular member to effect axial movement of said second tubular member upon rotation of said threaded tubular member, means to effect rotation of said threaded tubular member, keying means to restrain rotation of said second tubular member until it reaches one end of its travel, including a common keying and valve actuating element movable concurrently with said second tubular member, a longitudinally disposed key interengageable with respect to said element to hold said element and the second tubular member against unwanted rotation during axial movement of the latter, latch means normally holding the key against lateral movement but releasable by said element as the second tubular member reaches the end of its axial movement, and means responsive to lateral movement of the key for actuating the valve.

5. Means as set forth in claim 4 wherein said element comprises a disc secured to the second tubular member and having keying portions and camming portions engageable with said key and also having latch actuating portions engageable with said latch means.

6. Means as set forth in claim 4 wherein said element comprises a disc secured to the second tubular member and having peripheral keying portions and camming portions engageable with said key and also having latch actuating end face portions engageable with said latch means.

7. A soot blower construction comprising a housing having a passageway therein and a fluid inlet to the passageway, a valve for controlling the flow of fluid to said inlet and passageway, a tubular member rotatably carried by said housing and communicating internally with said passageway and having external driving thread portions thereon, a second tubular member surrounding the first tubular member and longitudinally slideable and rotatable with respect thereto, driven portions fixedly secured with respect to said second tubular member and engaging and drivable by said thread portions, shiftable keying means having a keying position in which it is adapted to

prevent unwanted rotation of said second tubular member during longitudinal travel of the latter, whereby said second tubular member may be driven longitudinally in response to rotation of said first tubular member, means supporting said keying means for independent shifting movement to and from keying position, means normally holding the keying means against such shifting movement including a releasable latch for maintaining said keying means in said keying position and which, when released, permits shifting of the keying means to a non-keying position and resultanty permits rotation of said second tubular member.

8. Means as set forth in claim 7, including a valve actuating element actuatable in response to release of said keying means.

9. Means as set forth in claim 7 wherein said keying means comprises a laterally movable bar, valve actuating means operatively connected to the bar and movable to actuate said valve in response to lateral movement of said bar out of the operative keying position, means to release said latch in response to attainment of a predetermined longitudinal position by said second tubular member, and a combined keying and camming element secured to and movable both longitudinally and rotatably with said second tubular member whereby said second tubular member is rotatable without longitudinal movement thereof, and whereby said bar may be moved laterally in response to rotation of said second tubular element after release of the latch, and the valve is actuatable by such rotation.

10. Means as set forth in claim 9 wherein release of said latch permits lateral movement of said bar in one direction only, spring means urging the bar in the opposite direction to that in which it is movable upon release of said latch, said combined keying and camming element comprising a cam having portions adapted to extend beside said bar when the same is latched, and

having peripheral portions adapted to maintain the bar in laterally displaced position during at least a part of the rotation of said second tubular member.

5 11. Means as set forth in claim 9 wherein said combined keying and camming element also carries a latch actuating portion for releasing said latch.

10 12. Means as set forth in claim 9 wherein said combined keying and camming element also carries a latch actuating portion for releasing said latch, and wherein release of said latch permits lateral movement of said bar in one direction only, spring means urging the bar in the opposite direction to that in which it is movable upon release of said latch, said combined keying and camming element comprising a cam having portions adapted to extend beside said bar when the same is latched, and having peripheral portions 20 adapted to maintain the bar in laterally displaced position during at least a part of the rotation of said second tubular member.

HARRY E. BRELSFORD.
